UNITED STATES PATENT OFFICE.

ANNA DUSELL PARRETT, OF DENVER, COLORADO.

BOOK.

1,220,884.

Specification of Letters Patent. Patented Mar. 27, 1917.

Application filed August 21, 1916. Serial No. 116,051.

To all whom it may concern:

Be it known that I, ANNA DUSELL PARRETT, a citizen of the United States, residing at Denver, in the county of Denver and State of Colorado, have invented certain new and useful Improvements in Books; and I do declare the following to be a full, clear, and exact description of the invention such as will enable others skilled in the art to which it appertains to make and use the same.

This invention relates to books and more particularly to books having envelop leaves or sheets.

15 The main object of the invention is to provide a book of this character of a size convenient to be carried in the pocket or handbag of the owner and having the leaves thereof folded to form a combined writing 20 sheet and envelop designed to contain messages or other matter to be reserved and read at set times, the flaps having spaces to receive directions relative to the opening of the envelop.

25 Another object of the invention is to provide a book of this character, the leaves of which are constructed to form pairs of envelops connected at the ends of the body portions thereof, the flaps on one envelop 30 being independent of those on the other.

With these and other objects in view, the invention consists of certain novel features of construction, and the combination and arrangement of parts as will be more fully 35 described and claimed.

In the accompanying drawings:

Figure 1 represents a perspective view of a book embodying this invention, in closed position;

40 Fig. 2 is a similar view showing the book open with one of the passage containing leaves in sealed condition ready for opening;

Fig. 3 is a similar view with parts broken 45 out showing the leaf open for perusal;

Fig. 4 is a perspective view showing the book open through its center, illustrating one manner of mounting the leaves and their connection; and,

50 Fig. 5 is a plan view of one of the leaves in open unfolded position.

In the embodiment illustrated the book constituting this invention which may be used as an album or for any other purpose 55 consists of a pair of connected covers 1 and 2 composed of a single rectangular sheet of

any suitable material such as heavy paper, cardboard, leatherette, or the like. This rectangular sheet is folded transversely midway its ends as shown at 3 to form a hinge-like connection between the covers, and the free ends of these covers may be provided with suitable means for connecting them, tapes 4 and 5 being here shown which are adapted to be tied together for holding the 60 covers in position, or the covers need not be fastened.

Bound between these covers are a plurality of envelop leaves 6 formed in connected pairs. Each pair of these connected 70 leaves is constructed from a single substantially rectangular sheet of paper, linen, or the like as best shown in Fig. 5. This sheet is of a length slightly less than the length of the combined covers 1 and 2 and of a 75 width greater than the width of said covers to provide for its being folded to form the envelop leaves 6 which are when formed, of a size substantially corresponding to the size of the individual covers. 80

The sheet from which each pair of connected envelops is formed is folded midway its length as indicated at 7 and this folded portion 7 is secured to the covers at their connected point by any suitable means such as stitching, staples, or the like. This sheet beyond the secured portion thereof is cut out to form pairs of separated top and bottom flaps carried by the respective leaves 6 which leaves are arranged at opposite 85 sides of the folding point 7 of the sheet, said folding point connecting the ends of the body portions of the two envelops. The top flaps 8 of the two connected envelop leaves 6 have lines of fold 9 formed at their 90 bases or points of connection with the body portions of the leaves, the folding line of the flap 8 of one of the leaves being arranged in longitudinal alinement with that of the other leaf with which it is connected 95 and extending flush with the upper end of the folding line 7 of the sheet. The cut out portion between the inner or adjacent ends of the two flaps 8 of the connected pairs of envelops is here shown V-shaped, and the 100 end edges of said flaps are inclined inwardly toward each other as shown at 10, and 11. The upper flaps which fold over may be any shape just so that they give the general 105 effect of folding over to conceal part of the lower portion.

The lower or bottom flaps 12 also have

lines of fold formed at their bases or points of connection with the body portion of their respective envelopes, the folding lines of the flap of one envelop being arranged in longitudinal alinement with the folding line of the flap of the other envelop with which it is connected and with the lower end of the line of fold 7 of the sheet from which the two envelopes are formed. The cut out portion between the inner or adjacent ends of these flaps 12 is preferably in the form of a rectangular strip so that these flaps 12 form extensions of the connected body portions of the leaves 6, being substantially of the same length and width as said body portions, so that when the sheet is folded to form the envelopes, these flaps 12 will lap over the inner face of the sheet proper with their free edges terminating adjacent the folding line of the upper flaps 8 whereby an extended space is formed for containing written or printed matter.

The top or upper flaps 8 may be provided with any suitable sealing means, the inner faces being gummed or separate seals provided as shown at 13, according to the wishes of the user.

Any desired number of pairs of envelop sheets or leaves constructed as above described may be bound between the covers 1 and 2 according to the uses for which the book is intended.

While this book may be employed for any purpose, it is essentially designed for use for containing hidden messages or directions which are written on the inner faces of the body portion of the envelopes and of the flaps 12 thereof, so that when the flaps 12 are folded inwardly and the outer or top flaps 8 folded thereover and secured, the matter contained on the inner face of this envelop sheet will be completely hidden. After the message has been written and the envelop

sealed, directions for opening the same may be written on the outer face of the flap 8 45 thereof.

This book may have any words or designs printed on the outer faces of the covers thereof to designate its contents.

A book constructed as above described 50 may be conveniently carried in the pocket or handbag of the owner and referred to at any desired time.

I claim as my invention:

1. A book comprising a pair of covers, a 55 plurality of envelopes bound between said covers and arranged in pairs, the envelopes of each pair being disposed end to end in longitudinal alinement having body portions the adjacent ends of which are united 60 to each other and to the covers to form a hinged connection between the envelopes and the covers.

2. A book comprising a pair of covers composed of a single rectangular sheet 65 folded transversely its ends, and a pair of envelopes disposed between said covers, said envelopes comprising two leaves and being composed of a substantially rectangular sheet folded midway its length, the fold 70 of said sheet being secured to said covers at their fold, a top and a bottom flap folded over each leaf, each top flap having its end edges inclined toward each other, the fold of the top flaps on each sheet being in alinement, the bottom flaps having their folds longitudinally alined, and means for sealing the respective top and bottom flaps together. 75

In testimony whereof I have hereunto set my hand in presence of two subscribing witnesses. 80

ANNA DUSELL PARRETT.
